CARBURETOR

Thomas M. Ball, Detroit, Mich., assignor to
Chrysler Corporation, Highland Park, Mich., a.
corporation of Delaware

Application May 13, 1949, Serial No. 93,135

9 Claims. (Cl. 261—41)

1

This invention relates to an improved internal combustion engine carburetor and more particularly to an improved step up or power jet therein.

It is now conventional practice to supply fluid from the reservoir of a carburetor to the fuel mixture passage thereof through a relatively small metering orifice which predetermines the economy mixture of the carburetor. When enrichment of the mixture is required for power a so-called step-up valve is opened in order to allow an additional supply of fuel to flow from the reservoir of the carburetor to the fuel mixture passage. In the present invention opening of this step-up valve is produced by a mechanism which is responsive to changes in manifold vacuum and which provides a plurality of step-ups. With this multiple step-up device a change from an economy mixture to a full power mixture is made by gradual increments. This has been found to be particularly desirable for use on engines equipped with a supercharger.

The term "manifold vacuum" as used herein is intended to refer to the partial vacuum which is present in varying degrees in the manifold downstream of the throttle valve under engine operating conditions, and which is determined by the relationship of engine speed to throttle position. The term "drop in manifold vacuum" refers to an increase in absolute pressure in the manifold.

In the drawings:

Fig. 1 is a sectional elevational view of a down draft carburetor having my multiple step-up device incorporated therein;

Fig. 2 is a fragmentary view of the multiple step-up device of Fig. 1 showing the parts in their respective positions after one step-up has occurred;

Fig. 3 is a fragmentary view similar to Fig. 2 but showing the parts in their respective positions after a second increment of step-up has occurred;

Fig. 4 is a fragmentary view of a modified step-up device;

Fig. 5 is a partial view of the device of Fig. 4 showing the relative position of the parts under high vacuum conditions;

Fig. 6 is a view similar to Fig. 5 but showing the position of the parts under medium vacuum conditions; and

Fig. 7 is a view similar to Fig. 5 but showing the position of the parts under low vacuum condition.

Referring to the drawings, the carburetor comprises an assembly of a body 10, an air horn 11,

an insulator 12 and a second body portion 13. The body portion 13 is secured to the engine intake manifold (not shown). A nipple 14 is adapted to be connected by a fuel line (not shown) to a source of supply of fuel such as a fuel pump (not shown). The air horn 11 is provided with a tubular part 15 which serves as an air inlet to a fuel mixture passage 16. The egress of the fuel mixture to the engine intake manifold is controlled by a throttle valve 17.

The body portion 10 of the carburetor is provided with a fuel reservoir 18 and the intake of fuel thereto from the nipple 14 is controlled by a needle valve 19 which is operated by a conventional float mechanism 20 which predetermines the fuel level in the reservoir.

The main fuel injection means controls the mixture with air of fuel passing through a metering jet 21. Tubular passage 22 connects jet 21 with mixture chamber 16 through an orifice 23. Tubular passage 24 which is connected via ducts 25 and 26 to atmosphere is concentrically disposed within passage 22 and provided with a plurality of holes 27 in its side walls. Air entering tubular passage 24 escapes through holes 27 and mixes with fuel in passage 22 and the atomized mixture is discharged from orifice 23.

Liquid for engine idling is drawn by manifold vacuum from passage 22 through idling tube 34 which is connected through a passage 37 to a passage 38. The latter passage has an orifice 39 open to the atmosphere and an orifice 40 operatively connected to an idling jet 41.

A mechanism 28 which includes the multiple step-up device referred to herein is adapted to vary the fuel mixture ratio in response to the degree of manifold vacuum. This mechanism includes a spring loaded piston 29 adapted to reciprocate in response to variations in manifold vacuum transmitted through an orifice 30 and a passage 31. A first valve 35 controls the flow of liquid fuel through an orifice 36 which connects the fuel reservoir 18 and the passage 22. A second valve 45 controls the flow of liquid fuel through an orifice 46 which connects the fuel reservoir 18 and the passage 22. Piston 29 is forced upward by a spring 47 which has a spring rate such that manifold vacuum in passage 31 can overcome it to retract piston 29 downwardly. Piston 29 carries an arm 48 which is secured thereto and adapted to reciprocate therewith. Valve stems 35 and 45 each penetrate an opening in arm 48 and each are provided with an upset head 49 and 50 respectively. A spring 51 surrounds valve stem 35 and reacts against arm 48.

and a washer 52 carried on valve stem 35. A similar spring 53 surrounds valve member 45 and reacts against arm 48 and a washer 54 carried by valve stem 45. A guide member 55 is received within an opening in arm 48 and serves to guide the latter as it slides up and down in response to movement of piston 29.

It should be noted that in Fig. 1 the valve stem 35 is shown as constructed of a shorter length than the valve stem 45 so that when both valves are closed as shown in Fig. 1 the offset head of stem 35 is in contact with arm 48 while the offset head 56 of arm 45 projects above the arm 48. It is apparent that when the manifold vacuum decreases in passage 31 sufficiently for the spring 47 to raise piston 29 and arm 48 upwardly that arm 48 will first lift valve stem 35 and thus open orifice 36 so that an additional amount of fuel will be delivered from the fuel reservoir 18 to passage 22 and the parts will assume the position shown in Fig. 2 with the orifice 36 open and the orifice 46 closed. Further decrease in manifold vacuum permits spring 47 to further elevate piston 29 and arm 48. The further elevation of arm 48 lifts valve stem 35 further but this has no effect upon the operation of the carburetor for the valve stem 35 was already clear of orifice 36. However, the further upward movement of arm 48 causes upset head 56 to engage arm 48 whereby valve stem 45 is lifted clear of orifice 46 thereby providing a still further passage for fuel from the fuel reservoir 18 to passage 22. There is thus provided a normal supply of fuel to the engine and two additional step-ups which may be brought into action upon decrease in manifold vacuum.

It should be noted that the washers 52 and 54 engage abutments on the valve stems 35 and 45 respectively and that the springs 51 and 53 urge the valve stems downwardly toward their valve closing positions.

Although a pair of valve stems 35 and 45 have been illustrated as controlled by arm 48, it should be understood that a larger number of valve stems could be employed to provide additional increments of power mixture of fuel and air if desired.

In Fig. 4 a modified form of the invention is illustrated. The function accomplished by this form of the invention is similar to that already described in reference to Figs. 1, 2 and 3 although the mechanical arrangement of parts is somewhat altered and a single orifice two stage valve is substituted for the pair of valves used in the Fig. 1 form of the invention. The arm 48' carried by the manifold vacuum responsive piston 29 is provided with an opening at 60 which a valve stem 62 penetrates. The carburetor body 10 is provided with a valve housing arrangement 64 having an axial passage therethrough. The axial passage in valve housing 64 has a restricted portion 66 and a valve seat 68 formed therein. The valve stem 62 is provided with a needle like extension 70 and an enlarged portion 72 having a tapered portion 74 adapted to cooperate with the valve seat 68. The needle like extension 70 is adapted to penetrate the restricted orifice 66. Thus when the portion 74 of the valve stem rests upon the seat 68 there is no flow of fuel through restricted portion 66. When the valve stem 62 rises enough so the portion 74 uncovers valve seat 68 fuel flows through the restricted orifice 66, but the quantity thereof is limited for the effective size of the orifice is reduced by the presence of the needle like extension 70. Further elevation of the valve stem 62 lifts the needle like

extension 70 out of the restricted orifice 66 so that its effective area is utilized and a larger flow of fuel to the carburetor is provided. There are thus provided valve positions which accommodate either no flow of fuel through the orifice 66, a first reduced quantity of fuel or a maximum quantity of fuel. In order to accomplish this and provide the three operative positions for valve stem 62 in response to movement of arm 48' and piston 29 certain springs are provided on valve stem 62. A pair of lock nuts 76 are threaded on to the upper end of stem 62 above arm 48'. A washer 78 circumscribes stem 62 and a pin 80 limits downward movement thereof. A spring 82 is retained between arm 48' and washer 78. A second pair of lock nuts 84 are threaded to the central portion of stem 62. A second spring 86 surrounds stem 62 and reacts against the lock nuts 84 and a washer 88 which loosely surrounds the lower portion of stem 62 and on occasion abuts against the upper surface of valve housing element 64. The enlarged portion 72 of valve stem 62 is provided with a shoulder 89 below washer 88. The spring 82 is relatively strong while the lower spring 86 is relatively weak.

Referring to Fig. 5, it will be seen that under high vacuum conditions the valve is completely closed with the tapered portion 74 of the valve stem in engagement with the valve seat 68 and springs 47, 82 and 86 cooperate to oppose the vacuum which maintains piston 29 in its downward position. On a first reduction in manifold vacuum the combined effect of the springs 47, 82 and 86 tends to elevate piston 29 and the parts assume the intermediate position illustrated in Fig. 6 in which spring 86 is compressed while spring 82 is extended and relaxed with the arm 48' in contact with lock nuts 76. Under these conditions the tapered portion 74 of the valve stem 62 is lifted above the valve seat 68 although the needle like extension 70 still penetrates the restricted orifice 66. On further reduction in manifold vacuum the combined effects of spring 47 and spring 86 further elevate the piston 29. This upward movement of piston 29 elevates arm 48', which through lock nuts 76, elevates valve stem 62 until washer 88 is lifted off valve housing element 64 and the spring 86 is allowed to extend until washer 86 engages shoulder 89. At this time the needle like extension 70 is lifted entirely out of the restricted orifice 66 to provide a maximum flow of fuel through the orifice 66. The spring 82 serves an additional useful purpose in that it permits piston 29 and arm 48' to overtravel relative to valve stem 62. This is desirable for it obviates the necessity of having piston 29 reach the bottom of its stroke simultaneously with the seating of the tapered portion 74 of valve stem 62 on valve seat 68. Thus, even though the valve seat 68 is engaged the vacuum may move piston 29 downward an additional increment.

I claim:

1. In a carburetor adapted to supply fuel to an internal combustion engine having vacuum producing means, means defining a fuel reservoir, means defining a fuel and air mixing chamber, means defining an open fluid passage connecting the reservoir and the mixing chamber, means defining first and second supplemental fluid passages connecting said reservoir and said chamber, a valve in each of said supplemental passages and a common operator for said valves operable to open one of said valves under a first vacuum condition in said vacuum producing

5. A carburetor adapted to supply fuel to an internal combustion engine having vacuum producing means and operable to open both of said valves under a second vacuum condition in said vacuum producing means.

2. In a carburetor adapted to supply fuel to an internal combustion engine having vacuum producing means, means defining a fuel reservoir, means defining a fuel and air mixing chamber, means defining an open fluid passage connecting the reservoir and the mixing chamber, means defining first and second supplemental fluid passages connecting said reservoir and said chamber, a valve in each of said supplemental passages, a movable element associated with said valves and operable to sequentially open said valves when moved in a first direction, a spring urging said element to move in said first direction and means defining a passage exposing said element to vacuum from said vacuum producing means to oppose said spring whereby under a first vacuum condition said spring moves said element sufficiently to open one of said valves and under a second vacuum condition said spring moves said element sufficiently to open both of said valves.

3. In a carburetor adapted to supply fuel to an internal combustion engine having vacuum producing means, means defining a fuel reservoir, means defining a fuel and air mixing chamber, means defining an open fluid passage connecting the reservoir and the mixing chamber, means defining first and second supplemental fluid passages connecting said reservoir and said chamber, a valve in each of said supplemental passages and a vacuum responsive device operably connected to one of said valves to open said valve when a predetermined vacuum condition exists in said vacuum producing means, said device having a lost motion connection with the other valve so that said last mentioned valve is opened when a second predetermined vacuum condition is obtained in said vacuum producing means.

4. In a carburetor adapted to supply fuel to an internal combustion engine having vacuum producing means, means defining a fuel reservoir, means defining a fuel and air mixing chamber, means defining first and second supplemental fluid passages connecting said reservoir and said chamber, a valve seat associated with each of said supplemental passages, a valve stem associated with each of said seats, a vacuum responsive device having a piston element adapted to move in a first direction in response to a decrease in vacuum in said vacuum producing means and to move in a second direction in response to an increase in said vacuum, means carried by said piston element and adapted to move one of said valve stems off of its associated seat in response to a predetermined movement of said piston element in said first direction and to move the other of said valve stems off of its associated seat in response to continued movement of said piston element in said first direction.

5. In a carburetor adapted to supply fuel to an internal combustion engine having vacuum producing means, means defining a fuel reservoir, means defining a fuel and air mixing chamber, means defining an open fluid passage connecting the reservoir and the mixing chamber, means defining a supplemental fuel passage connecting said reservoir and said chamber, a valve adapted to control the flow of fuel through said supplemental passage, said valve including a movable stem having a first open position adapted to ac-

commodate a maximum flow of fuel through said supplemental passage, a second open position adapted to accommodate a reduced flow of fuel through said supplemental passage and a closed position which prevents the flow of any fuel through said supplemental passage, a control element, passage forming means to expose said control element to vacuum in said vacuum producing means to thereby induce movement of said control element in a first direction in response to increased vacuum conditions in said vacuum producing means, a first spring means opposing all motion of said element in said first direction and operable to urge said control element in the opposite direction and force transmitting means operably connecting said control element and said valve stem and adapted to position said valve stem in said positions in response to movement of said control element, said force transmitting means including second and third spring means positioned to progressively increase the opposition to motion of said control element in said first direction during predetermined stages of its movement in said first direction.

6. In a carburetor adapted to supply fuel to an internal combustion engine having vacuum producing means, means defining a fuel reservoir, means defining a fuel and air mixing chamber, means defining an open fluid passage connecting the reservoir and the mixing chamber, means defining a supplemental fuel passage connecting said reservoir and said chamber, a single orifice two stage valve controlling the flow of fuel through said supplemental passage, said valve having a valve stem mounted for linear movement, a vacuum responsive device mounted for linear movement in response to variations in vacuum in said vacuum producing means, an arm carried by said device, a fixed abutment positioned adjacent said stem, a first spring interposed between said arm and said stem and adapted to oppose movement of said arm in one direction relative to said stem, said stem having an abutment engageable by said arm to accommodate movement of said stem with said arm when said arm moves in a second direction, a second spring having one end abutting a portion of said stem and the other end positioned to engage said fixed abutment whereby under a first vacuum condition movement of said arm in said first direction by said device is opposed by both of said springs and movement of said stem with said arm in said second direction is facilitated by cooperation of said arm with the abutment on said stem and the movement in this second direction is assisted by said second spring.

7. A carburetor adapted to supply fuel to an internal combustion engine having a manifold and means for producing a vacuum in said manifold, said carburetor including a body part defining a fuel reservoir, an air and fuel mixing chamber and a main fuel passage connecting said reservoir and said mixing chamber, said body part being provided with auxiliary fuel passage means operably interposed between said fuel reservoir and said mixing chamber and adapted to provide an additional supply of fuel for said mixing chamber, valve means movable to a closed position, an open position and a restricted flow position relative to said auxiliary fluid flow passage means, a piston slidably mounted in said body part for movement in response to variations in manifold vacuum, an arm carried by said piston and first and second springs positioned to sequentially oppose movement of said arm and

provide a lost motion connection between said arm and said valve means to accommodate abrupt movement of said valve means to said positions in response to movement of said piston.

8. A carburetor adapted to supply fuel to an internal combustion engine having a manifold and means for producing a vacuum in said manifold, said carburetor including a body part defining a fuel reservoir, an air and fuel mixing chamber and a main fuel passage connecting said reservoir and said mixing chamber, said body part being provided with auxiliary fuel passage means operably interposed between said fuel reservoir and said mixing chamber and adapted to provide an additional supply of fuel for said mixing chamber, valve means movable to a closed position, an open position and a restricted flow position relative to said auxiliary fluid flow passage means, a spring opposed pressure differential operated element mounted for movement in response to variations in manifold vacuum, a member carried by said element and having a lost motion connection with said valve means and first and second springs acting upon said valve means and operable to move said valve means rapidly from said closed position to its restricted flow position and to its open position at predetermined conditions of manifold vacuum.

9. A carburetor adapted to supply fuel to an internal combustion engine having a manifold and means for producing a vacuum in said manifold, said carburetor including a body part defining a fuel reservoir, an air and fuel mixing chamber and a main fuel passage connecting said reservoir and said mixing chamber, said body part being provided with auxiliary fuel passage means operably interposed between said fuel reservoir and said mixing chamber and adapted to provide an additional supply of fuel for said mixing chamber, valve means movable to a closed position, an open position and a restricted flow position relative to said auxiliary fluid flow passage means, a pressure differential operated element mounted

5 for movement in response to variations in manifold vacuum, a first spring operable to move said element in response to decrease in manifold vacuum, a member carried by said element and having a lost motion connection with said valve means so that a first increment of movement of said element by said first spring occurs when manifold vacuum decreases without opening said valve means, a second spring acting upon said member and said valve means and cooperating with said first spring during the aforementioned first increment of movement, said second spring being operable only during relative movement between said member and said valve means, a third spring acting upon said valve means and reacting upon said body part during a portion of the movement of said valve means from its closed position to its open position and means carried by said valve means and operable to carry said third spring out of operative relation with said body part when said valve means has moved a predetermined amount in a direction tending to open said valve.
